2 Claims. (Cl. 273—96)

This invention relates to a toy responding to a constructive conception embodied by a functional unit comprised by a support in the shape of a platform from which a handle extends; from the upper face of said platform project two shoulders coaxially in coincident alignment with the upper end of the handle; between said shoulders a swing beam is pivotally mounted, bearing on the upper face of one of its ends a cup and on the upper face of its other end a projection arranged in coincident alignment with the geometric center of the lower mouth of a recipient containing a ball made of light material; said container being linked to that end of the platform with which the end of the swing beam provided with the projection registers and on a higher plane with respect thereto; from the end of the platform with which that of the swingbeam provided with the cup registers extends a string to whose opposite end a small ball made of heavy material is fastened.

The device whose essence has been pointed out in the foregoing paragraph embodies a modified version of the classic cup and ball plaything, inasmuch as when the small ball made of heavy material is whirled by displacements imparted to the platform by means of the handle and said small ball drops into the cup, the swing beam is subjected to an abrupt rocking movement followed by the oscillatory displacement of the projection towards the ball lodged in the recipient and which is expelled, by the impact of said projection, from said recipient in ascending flight.

The interesting feature of the device in question consists, as far as the functional aspect is concerned, in proceeding with due dexterity to, on the one hand, prevent the small ball from being chucked out of the cup under the effect of the repulse due to the strong angular displacement of the swing beam owing to the collision of said small ball with the bottom thereof, and on the other hand, to interpose the upper mouth of the recipient within the dropping path of the ball in order to receive the same with a view to compute the marks or hits, the prize being double when the small ball and the ball remain lodged within their respective recipients at the end of each playing period.

The device to which the present invention relates will now be described hereinafter completely in accordance with the accompanying drawing wherein:

Figure 1 is a view in lateral elevation of the device according to this invention and which is shown at the initial stage of the game.

Figure 2 is an elevational view of the device shown in section according to plane A—A of Figure 1, and

Figure 3 is a view in lateral elevation of the device shown at the final stage of the game.

In these views the same reference numerals and letters indicate equal or corresponding parts.

In connection with the accompanying drawing the device according to this invention will now be described; it comprises, wholly in keeping with what has been spe-

2

cified hereinbefore: a support *a* in the shape of a platform from the lower face of which extends a handle *1*. From the upper face of said platform project two lateral shoulders *2* arranged coaxially in coincident alignment with the upper end of handle *1*, a swing beam *b*, being pivotally mounted by means of a pin *3* between said shoulders, said pin being the supporting and guiding shaft for the rocking play of said swing beam.

The swing beam *b* is arranged at a sufficient height from the upper face of platform *a* to allow the oscillatory play of the same within the required magnitude for the normal development of the game, the forearm *4* of said swing beam being smaller than arm *5*.

To the free end of arm *4*, i.e., to its upper face a cup *6* is secured, and to the free end of arm *5*, i.e., also to the upper face thereof, a projection *7* is secured in coincident alignment with the geometric center of the lower mouth of a recipient *8* containing a ball *9* made of light material and which emerges slightly from said lower mouth.

The recipient *8* is linked to the upper face of platform *a* by means of the stays *10* so dimensioned as to allow the lower mouth of said recipient to remain at a height such as to cause the impacts of the projection *7* on the ball *9* to be efficient.

From that end of platform *a* with which the end of arm *4* provided with cup *6* registers extends a string *11* to whose free end is attached a small ball *12* made of heavy material, preferably lead, and which constitutes the active means for the development of the game.

The development of the game is as follows: by means of handle *1* platform *a* is maneuvered to a degree such as to cause the small ball *12* freely suspending from string *11* to whirl, when it is tried to have the same land within cup *6* which, owing to the impact of said small ball, imparts to arm *4* of swing beam *b* and angular displacement in the sense of arrow *F* of Figure 1 and, thereupon, to arm *5* the one indicated by arrow *F1*, thereby bringing about a heavy impact of projection *7* on such portion of ball *9* as emerges from the lower mouth of recipient *8*, which ball is thus pushed through the upper mouth of said recipient. Therefore, if the player goes about with sufficient dexterity to place the recipient within the dropping path of the ball and get it landed inside said recipient, a given amount of hits is credited in his favor, and if his dexterity reaches a climax such as to prevent the small ball *12* from leaving cup *6*, the amount of hits will be doubled. The importance of the device as a pastime will be inferred herefrom.

It is obvious that ulterior detail modifications may be introduced in the unit constituting the device of the present invention as may be suggested by practice and without thereby departing from the scope of the following claiming clauses.

We claim:

1. A toy of the class described comprising a bearing platform, a pair of laterally aligned shoulders projecting above said platform, a beam pivoted intermediate its ends on said shoulders, a ball receiving cup fixed to one end of said beam and a projection extending upwardly from the other end of said beam, a tapered receptacle open at its opposite ends and adapted to receive a relatively large ball with a diameter sufficiently great to prevent its complete emergence from the lower end of the receptacle, means supporting said receptacle on said platform with its lower open end out of contact therewith and with the axis of the receptacle in alignment with the axis of the projection, a second ball having a smaller diameter than said first ball and being adapted to be received in said cup, a string tethering said second

ball to said platform adjacent said cup, and a handle secured to said platform for maneuvering said device to swing said second ball into said cup, whereby the beam will be swung about its pivot causing the projection thereon to strike the ball in said receptacle and drive it out of the upper open end thereof.

2. The device of claim 1, wherein the portion of the beam between its pivot and the cup is of shorter length than the length of the beam between its pivot and the receptacle.
